IRA DIMOCK, OF FLORENCE, MASSACHUSETTS.

Letters Patent No. 83,264, dated October 20, 1868.

APPARATUS FOR BOILING EGGS.

The Schedule referred to in these Letters Patent and making part of the same.

To all whom it may concern:

Be it known that I, IRA DIMOCK, of Florence, in the county of Hampshire, and State of Massachusetts, have invented a new and improved Apparatus for Boiling Eggs; and I do hereby declare that the following is a full, clear, and exact description thereof, which will enable those skilled in the art to make and use the same, reference being had to the accompanying drawings, forming part of this specification, in which—

Figure 1 is a sectional elevation of my invention.

Figure 2 is a detail top view of the adjusting-boss, part of which is partially broken away, to exhibit its construction more clearly.

Figure 3 is a perspective detail view of the adjusting-cap.

Figure 4 is a perspective detail view of the boss at the upper end of the spindle.

Similar letters of reference indicate corresponding parts.

My invention relates to apparatus to be used for boiling eggs and like purposes, which will indicate or give notice when a given degree of combined time and temperature has been arrived at.

My invention consists in placing a fluid which will expand by heat, in a case, and in surrounding such case by another case, so as to leave an air-cavity, or with some substance which is a slow conductor of heat.

The quantity of liquid in the case, the extent of the cavity for air, or the thickness of the slow heat-conducting substance, is so proportioned that when used, say, for boiling eggs, the liquid within the instrument will have attained a given degree of expansion by the time the eggs are properly cooked, and this will be the case whether the eggs are placed in cold or boiling water.

My invention also consists in showing the degree of expansion in the fluid, within the case above referred to, by causing it to act upon a piston in a cylinder, or act upon a diaphragm, which piston or diaphragm is made to transmit the motion to a latch or catch, which holds a hammer, and allows it to strike a bell, and thus announce by sound that the proper degree of heat has been arrived at.

Though a liquid has been mentioned as the medium through which heat is transmitted to the eggs to be cooked, yet the apparatus will act when the eggs are exposed to the action of steam, or a hot bath of sand or other suitable substance.

The manner in which my invention is carried into effect is illustrated in the accompanying drawings.

In the drawings, my apparatus is shown to consist of a receptacle for holding the eggs, (which receptacle may be a rack, basket, or frame-work, of wire or other suitable metal, or material capable of undergoing heat without destruction,) combined with and forming part

of a thermo-annunciator, the construction and operation of which will now be particularly set forth.

The thermo-annunciator consists of an inner cylindrical case, *b*, closed at its lower end, and resting upon another case, *c*, (as shown,) of larger diameter, so as to leave a space for air.

The upper end of the cylindrical case *b* is closed by an India-rubber diaphragm, *b*², and this is secured by a cap, *c*¹, which screws upon the outer case, *c*, and also secures the flange of a vertical tube, *c*².

Within this tube a plug or piston, *d*¹, is fitted, which can slide freely up and down in the tube *c*², but is prevented from turning round by a pin, *g*, fixed in the side of the tube *c*², and passing into a slot in the plug or piston *d*¹.

The lower end of a spindle, *d*, is made to screw into the plug or piston *d*¹, and the upper end of this spindle slides through a bush, *h*, fixed in the tube *c*², and around the spindle *d* a helical spring, *k*, is placed, one end of which acts against the bush *h*, and the other end against the plug or piston *d*¹.

To the upper end of the spindle *d*, a boss, *d*², is secured, which is recessed upon its under side, so that it may form a catch all round, for the hook *f*², of the hammer *e*, to take hold of, this hammer being placed on a fulcrum, *f*¹, in a slot in the bush *h*, which comes opposite a slot in the side of the tube *c*².

The hammer *e* falls by its own weight, but it is assisted in its descent by a spring, *f*¹, acting upon a tail-part from the hammer-lever, which spring is secured to the inside of the tube *c*².

The hammer *e* is intended to form a handle to lift the instrument by, so that the act of lifting will cause the incline upon the hammer-lever to act upon the incline around the boss *d*², and force the spindle *d* upwards until the incline-surfaces can pass, when the weight of the spindle *d* and other attached parts, and the force of the spring *k*, will cause the spindle *d* to descend, so as to hold the hammer *e* in the position shown by fig. 1.

A cap, *l*, forming a screw-head, is also attached to the upper end of the spindle *d*, by a screw, *l*¹. This is milled upon the edge, so that it can be turned when required, and the index-marks are placed upon the upper face, as shown in fig. 2; and there is a pointer, *e*², upon the hammer-lever, by which to set the index.

There are vertical grooves in the side of the boss-part *l*, one for each mark upon the index; and a screw, *l*², is passed through the side of the tube *c*², the point of which will enter one of the slots.

By pulling the head, *l*, upwards until the end of the screw *l*² comes opposite a groove, *l*³, passing round the boss, the head, *l*, can be turned, as required, until the point of the screw comes opposite the groove corresponding to the mark upon the index to which the instrument is to be set.

The index is secured, when adjusted, by a pin in the head, *l*, which passes into a hole in the boss *d*².

The bell *e*¹ is fixed upon the exterior of the tube *c*², as shown.

When the fluid within the case *b* has become heated sufficiently to cause it to expand, the diaphragm, in yielding, permits such expansion to be felt by the spindle *d*, raising it, and thus liberating the hammer *e*, which latter descends and strikes upon the bell *e*¹, thus announcing that the proper degree of heat has acted upon the eggs.

Modifications of my invention may be made, as, for example, those shown and described in a patent granted to me in England, September 30, 1867, (No. 2,750,) in all of which are employed the non-conducting cases, which retard the penetration of heat, so that a sufficient time for cooking the eggs will elapse before the fluid within the inner case will be made to expand, and thus announce the fact, by actuating a piston or diaphragm, and its accessory mechanism, or by raising the said fluid to a certain height on a scale.

I desire to be understood as not limiting myself to the precise arrangement or construction of the parts of the bell-hammer and its catch-mechanism, for the same may be variously modified without departing from the general features of my invention.

I claim as new, and desire to secure by Letters Patent—

1. The use, in an apparatus for boiling eggs, of a fluid, surrounded by a slow heat-conducting material or air-cavity, substantially as described, in combination with a bell or other sonorous annunciator, the striking-hammer of which is actuated to strike the same, from the expansion of the said fluid, all as set forth.

2. The use of a fluid in a case arranged to act, by expansion, on a piston or diaphragm, which will transmit movement, so as to release a catch and ring a bell, all substantially as shown and described, and for the purpose set forth.

3. An egg-boiling apparatus, when constructed substantially as herein shown and described.

4. The combination, in an egg-boiling apparatus, of an egg-receptacle, *a*¹, of any suitable form, with a case, *b*, enclosed by another case, *c*, to retard the penetration of heat to a fluid within the inner case, substantially as described.

IRA DIMOCK.
